UNITED STATES PATENT OFFICE.

HARRY STONE, OF CHICAGO, ILLINOIS.

DESIGN FOR A LAMP SHADE.

Application filed May 16, 1927. Serial No. 22,001. Term of patent 3½ years.

To all whom it may concern:

Be it known that I, HARRY STONE, a citizen of the United States, residing at Chicago, in the county of Cook and State of Illinois, have invented a new, original, and ornamental Design for Lamp Shades, of which the following is a specification, reference being had to the accompanying drawing, forming part thereof.

The figure is a side elevation of a lamp shade showing my new design, and in said figure the portion shown in full lines is regarded as the dominant feature of the design.

I claim:

The ornamental design for a lamp shade, as shown and described.

HARRY STONE.
